The ornamental design for a bath tub drain cover as shown
and described.

DESCRIPTION

FIG. 1 is a top perspective view of a bath tub drain cover in
a retracted state showing my new design;

FIG. 2 is a bottom perspective view of the bath tub drain
cover in the retracted state;

FIG. 3 is a front elevation view of the bath tub drain cover
in the retracted state;

FIG. 4 is a rear elevation view of the bath tub drain cover in
the retracted state;

FIG. 5 is a left elevation view of the bath tub drain cover in
the retracted state;

FIG. 6 is a right elevation view of the bath tub drain cover in
the retracted state;

FIG. 7 is a top plan view of the bath tub drain cover in the
retracted state;

FIG. 8 is a bottom plan view of the bath tub drain cover in
the retracted state;

FIG. 9 is a sectional view taken line along line 9-9 of FIG.
7 showing the bath tub drain cover in the retracted state;

FIG. 10 is a top perspective view of the bath tub drain cover
in an extended state showing my new design;

FIG. 11 is a bottom perspective view of the bath tub drain
cover in the extended state;

FIG. 12 is a front elevation view of the bath tub drain cover
in the extended state;

FIG. 13 is a rear elevation view of the bath tub drain cover
in the extended state;

FIG. 14 is a left elevation view of the bath tub drain cover
in the extended state;

FIG. 15 is a right elevation view of the bath tub drain cover
in the extended state;

FIG. 16 is a top plan view of the bath tub drain cover in the
extended state;

FIG. 17 is a bottom plan view of the bath tub drain cover in
the extended state;

FIG. 18 is a sectional view taken along line 18-18 of FIG. 16
showing the drain cover in the extended state;

FIG. 19 is a top perspective view of the bath tub drain cover
in a transitional state, which is between the retracted state
and the extended state, showing my new design;

FIG. 20 is a bottom perspective view of the bath tub drain
cover in the transitional state;

FIG. 21 is a front elevation view of the bath tub drain cover
in the transitional state;

FIG. 22 is a rear elevation view of the bath tub drain cover
in the transitional state;

(Continued)

FIG. 23 is a left elevation view of the bath tub drain cover in the transitional state;

FIG. 24 is a right elevation view of the bath tub drain cover in the transitional state;

FIG. 25 is a top plan view of the bath tub drain cover in the transitional state;

FIG. 26 is a bottom plan view of the bath tub drain cover in the transitional state; and,

FIG. 27 is a sectional view taken along line 27-27 of FIG. 25 showing the bath tub drain cover in the transitional state. The dashed broken lines in the drawings are for the purpose of illustrating unclaimed portions of the bath tub drain cover and form no part of the claimed design.
